JOSHUA C. CONRAD, OF CEMENT, OKLAHOMA

COTTON HULLING AND CLEANING MACHINE

Application filed May 23, 1929. Serial No. 365,429.

This invention relates to a cotton hulling and cleaning machine, especially adapted for extracting hulls from bollie cotton, that cotton which has not attained maturity, but which is also adapted for cleaning all kinds of cotton, including hand picked cotton, to better prepare it for the ginning operation.

One of the objects of the invention is to provide a machine of the indicated character which will embody improvements in the construction and operation thereof, to the end that cotton may be hulled and/or cleaned in a thorough and efficient manner.

Another object of the invention is the provision in a machine of the indicated character of improved means adapted to subject the bolls to a beating action, and to blasts of air, simultaneously, in the presence of a screen for the purpose of extracting the hulls from the cotton, and also cleaning the cotton by separating small trash, stems, dust and other foreign matter therefrom.

Another object of the invention is the provision in a machine of the combination of a movable endless belt having picker points and beaters which cooperate therewith for hulling bolls and for cleaning cotton.

Another object of the invention is the provision of improved forms of beaters for a machine of the character mentioned.

With the foregoing and other objects in view, the invention resides in the particular construction and operation of the parts, and combinations of said parts, hereinafter fully described and illustrated in the accompanying drawings, in which:

Figure 1 is a diagrammatic side view of a machine embodying the features of the present invention.

Figs. 2 and 2^a represent a longitudinal sectional view of the machine, portions being broken away.

Fig. 3 is a transverse sectional view of one of the beaters, the section being taken on the line 3-3 of Fig. 4.

Fig. 4 is a sectional view of one end of the beater shown in Fig. 3, the section being taken on the line 4-4 of Fig. 3.

Fig. 5 is a transverse sectional view of an

other form of beater, the section being taken on the line 5-5 of Fig. 6.

Fig. 6 is a sectional view of one end of the beater shown in Fig. 5, the section being taken on the line 6-6 of Fig. 5.

Fig. 7 is a sectional view of a cotton feeder.

Figs. 8 and 9 represent other forms of beaters.

Referring now to the drawings, and more particularly to Figs. 2 and 2^a, it will be apparent, that the machine of the present invention includes a supporting frame structure 10, which supports a casing 11 of suitable construction. The casing at one end has a feed hopper or chute 12 for feeding the bolls or cotton into the casing 11 through the inlet 13. The casing 11 also is provided with an outlet chute 14 for the seed cotton, and an outlet 15 for the hulls, stems and large pieces of trash. Arranged within the casing 11 near the top 16 thereof but spaced a suitable distance below the same are drums 17 and 18 respectively mounted to rotate with shafts 19 and 20 extending transversely of the casing 11. The opposite ends of the shaft 19 are journaled in suitable bearings on the frame 10, and said shaft 20 also has the opposite ends journaled in slidable bearings 21, on the frame 10. An endless band or belt 22 encircles the drums 17 and 18, and is provided with teeth, picker points or pins 23 disposed at an angle with respect to the surface of the band or belt. Preferably the band or belt 22 will be made of card clothing, but any other suitable band or belt may be used.

Arranged in the chamber 24 below the belt 22 are beaters which may be of any preferred types to cooperate with the belt 22 in carrying out the hulling and cleaning operations. Any suitable number and arrangement of beaters of any preferred types may be provided to cooperate with the belt 22 in carrying out the hulling and cleaning operations. In the present instance there are two beaters 25 of one type to be hereinafter described, and five beaters 26 of another type to be hereinafter described. The beaters 25 and 26 are mounted to rotate respectively with shafts 27, 28, 29, 30, 31, 32 and 33 journaled in suitable bearings on the frame structure 10. A breaker

60

65

70

75

80

85

90

95

or crusher 34 is arranged within the chamber 24 at the inlet 13. The breaker or crusher 34 is mounted on a shaft 35 journaled in suitable bearings on the frame 10. A screen 36 is arranged within the casing 11 below the beaters 25 and 26, and forms the bottom of the chamber 24. The screen 36 is undulated so as to accommodate the beaters 25 and 26 and present in cooperative relation therewith a maximum screening surface. The casing 11 is constructed to provide a hopper 37 below the screen 36. A spiral conveyor 38 is arranged inside of the hopper 37 at the bottom thereof for a purpose to appear. A stripper roller 39 of any preferred type is arranged transversely within one end of the casing 11 to cooperate with the belt 22. The roller 39 is mounted on a shaft 40 having its opposite ends respectively journaled in bearings 41. The bearings 21 which support the shaft 20, and the bearings 41 which support the shaft 40 are secured to plates or the like 42 respectively on opposite sides of the frame 10. Each plate 42 is slidably mounted so as to be adjustable, and this is accomplished by the provision of a screw 43 having one end turnably connected with a lug 44 on the plate and said screw being in threading engagement with a lug 45 on said frame. The screw 43 has a hand wheel 46 for manipulating the same. It will now be understood that by manipulating the screws 43, the belt 22 is tightened thereby causing the lower lead thereof to be raised or lowered relative to the beaters 25 and 26, in order to obtain the desired cooperation thereof when separating hulls from the cotton, or when cleaning hand picked cotton. The roller 39 will be adjustable with the drum 18 in the manipulation of the screws 43 so as to properly cooperate with the belt 22. The upper lead of the belt 22 rests on a suitable support 47 supported by the side walls of the casing 11. Stripper rollers 48 and 50 and brush 49, like the roller 39 are arranged within the casing 11, above the upper lead to cooperate therewith for a purpose to appear. The roller 48, brush 49 and roller 50 are mounted respectively to rotate with shafts 51, 52 and 53 journaled in suitable bearings on the frame 10. A doffer brush 54 is arranged within the casing 11 directly above the drum 17 at the entrance to the outlet chute 14 and is mounted to rotate with a shaft 55 journaled in suitable bearings on the frame 10. A spiral conveyor 56 is arranged below the stripper roller 39 and includes a trough 57 within the casing 11 and a chute 58 on the outside of the casing 11, the upper end of the chute communicating with the trough 57 and the lower end thereof communicating with the chamber 24 as at 59. A spiral conveyor 60 including a trough 61 and chute 62 cooperate with each one of the stripper rollers 48 and 50, said chute 62 converging to a common opening 63 in communication with the chamber 24.

Suitable driving means is provided for driving the beaters 25 and 26 in the same direction, and the breaker or crusher 34 in an opposite direction. The breaker or crusher 34 is rotated in a clockwise direction, and the beaters 25 and 26 are therefore rotated in a counter clockwise direction when it is desired to separate the hulls from the cotton. The drums 17 and 18 will be rotated in a counter clockwise direction, also the stripper rollers 39, 48 and 50, whereas the brush roller 49 and the doffer brush 54 will be rotated in a clockwise direction. The driving means is illustrated most clearly in Fig. 1, the showing being diagrammatic. It will be apparent that the drive shaft 64 transmits motion to the shaft 23 by pulleys and a belt 65. The shaft 28 transmits motion to the shafts 19 and 27 by pulleys and belts 66 and 67. The drive shaft 64 transmits motion to the beater or crusher shaft 35 by pulleys and a twisted belt 68. The shaft 35 transmits motion to the shaft 31 by pulleys and a twisted belt 69. The shaft 31 transmits motion to the shaft 51 by pulleys and a belt 71. The shaft 51 transmits motion to the shaft 53 by pulleys and a belt 72. The shaft 31 transmits motion to the shaft 29 by pulleys and a belt 73. The shaft 29 transmits motion to the shaft 30 by pulleys and a belt 74. The drive shaft 64 transmits motion to the shaft of one of the conveyors 60 by pulleys and a belt 75, and the other conveyor 60 is operated from the first conveyor by pulleys and a belt 76, while pulleys and a belt 77 operate the conveyor 56 from the intermediate conveyor 60. Motion is transmitted from the shaft 29 to the shaft 55 of the doffer brush by pulleys and a twisted belt 78. Motion is transmitted from the shaft 55 to the shaft 52 by pulleys and a belt 79. Motion is transmitted from the shaft 30 to the shaft of the conveyor 38 by pulleys and a belt 80.

From the foregoing it will be apparent that when it is desired to separate hulls from the cotton of bollie cotton, the bolls are fed into the chamber 24 of the machine. The breaker or crusher 34 will crush unopened or closed bolls, and these crushed bolls will pass from under the breaker or crusher 34 to the beaters 25 and 26. The beaters 25 and 26, in accordance with the invention are designed and adapted to cooperate with the belt 22 to set up both mechanical and pneumatic action, to extract or separate the hulls from the cotton. The action will be continuous, and cotton will be carried around by the belt 22 in the presence of the stripper rollers, due to the fact that cotton is caught on the teeth,

picker points or pins 23 on the belt, together with some hulls and trash. The stripper rollers allow the cotton to pass along with the belt, but hulls, trash and some cotton are thrown back by the stripper roller 39 to the beaters, the matter entering the trough of the conveyor 56 and thus returning to the chamber 24. The other stripper rollers 48 and 50 remove any remaining hulls; the rollers 48 and 50 removing said hulls into their related troughs 57 to be returned to the chamber 24. This expedient is resorted to in order to effect a thorough separation of the hulls from the cotton. When the machine is operating, the 15 hulls fall back on the beaters, and are eventually ejected or pass out of the outlet 15 together with stems and large fragments of trash. The cotton travels around with the belt 22 and is removed by the brush 54 into the outlet chute 14 from which it may be conveyed to any suitable point. The smaller fragments of trash, dirt, dust and other foreign matter is separated from the cotton by the screen 36, and is carried off by the conveyor 38 at the bottom of the hopper 37 to any suitable point of disposal. It will therefore be apparent that the cotton is subjected to a thorough cleaning process, due to the fact that it is shaken up and thrown against 20 the under or lower lead of the belt 22, by the action of the beaters.

When it is desired to use the machine as a cleaner, the beaters may be caused to rotate in the same direction as breaker or crusher 34, by rearrangement of the belts for that purpose. Hand picked cotton fed into the chamber 24 through the inlet 13 will be moved along by the beaters in the presence of the screen 36 and all impurities will be separated therefrom. The cotton will be delivered out of an opening in the wall of an outlet 15 which is controlled by a valve member 81, by moving said valve member 81 to the position shown in dot and dash lines in Fig. 2. The 45 impurities or other foreign matter will drop into the hopper 37 to be carried off by the conveyor 38. It will be obvious that if the machine is used in conjunction with a gin, the cotton will be cleaned in a beneficial manner 50 to better prepare it for the ginning operation.

As before stated, any suitable types of beaters may be used in conjunction with the belt and screen, and that it is also contemplated to carry out cleaning operations as well as hull extracting operations pneumatically. As regards the mechanical phase of cleaning and extracting the hulls, the beaters may consist of a shaft 85 having rods disposed transversely thereof to present radial beater members 86, as shown in Fig. 8. The type of beater shown in Fig. 9 may also be used consisting of a shaft 87 having mounted thereon a drum 88, the cylindrical wall 89 of 60 which is made up of wood lagging having

spikes 90 driven therein to present beater members. In accordance with the pneumatic phase use may be made of a beater of the type disclosed in Figs. 3 and 4. Such beater includes a cylindrical body 91 having a head or disk 92 at each end. A hub 93 having spokes 94 is connected with each disk or head 92, and this is accomplished by securing said spokes 94 to said disk or head 92 in any suitable manner. Blade-like beater members 95 each have the opposite ends thereof respectively fastened in any suitable manner as at 96 to flanges 97 on the heads 92. The body 91 is provided with air openings 98 in the form of slots extending lengthwise of the body 91 adjacent the members 95 respectively. The hubs 93 are adapted to accommodate a shaft 99 to which the hubs are fastened. The shaft 99 will have the opposite ends thereof journaled in bearings outside of the casing of the machine, and the wall of the casing adjacent each head 92 will be provided with an opening 100 for the admission of air into the body 91. It will therefore be understood that when the beater is in motion blasts of air will be caused to flow from the openings 98, and in conjunction with the action of the beater members 95 will effectively subject the material to a beating and blowing action. As shown in Figs. 5 and 6 a beater is produced from a single length of pipe 105 having air openings 106 in the form of slots extending longitudinally thereof. Blade-like beater members 107 are welded to the pipe 105 respectively adjacent said openings 106 disposed parallel thereto, or in other words longitudinally of the pipe 105. An element consisting of a hub 108 and spokes 109 is arranged in each end of the pipe 105, said spokes being secured as at 110 to said pipe 105. It will be apparent that this type of beater will function similarly to the type of beater shown in Figs. 3 and 4. This type of beater has been illustrated in Figs. 2 and 2^a designated 26.

In Fig. 7 of the drawing there has been shown a modified form of device embodying the mechanical and pneumatic features hereinabove set forth, and serves as a cleaner of hand picked cotton and also as a feeder, for feeding the clean cotton into a gin. The device includes a casing 115 having an inlet 116 and an outlet 117. The casing 115 is substantially cylindrical, and is provided with a hinged door 118 to afford access to the interior thereof. Arranged within the casing 115 is a beater 119 of the type shown in Figs. 3 and 4. A screen 120 is arranged between the cylindrical wall of the casing and the periphery of the beater 119. Feeding elements 121 are arranged within the casing at the inlet 116 to feed the cotton to the beater 119. A spiral conveyor 122 extending into the casing 115 below the screen serves to carry away trash, dust and other foreign matter 125 130 135

separated from the cotton in the cleaning operation. The cotton is cleaned by the action of the beater 119 in conjunction with the screen 120, said beater functioning to subject the cotton to a beating action while forcing currents of air through the cotton in the rotation of the beater.

I claim:

1. A cotton huller and cleaner, including an endless movable belt having picker points, beaters arranged to discharge material into the operative area of said belt to separate the hulls from the cotton, and a screen below said beaters, to separate the dirt and trash from the cotton as the cotton is being subjected to the action of the beaters and said belt.

2. A cotton huller and cleaner, including an endless movable belt having picker points, beaters arranged to throw material against the surface of said belt to separate the hulls from the cotton, a screen below said beaters, to separate the dirt and trash from the cotton as the cotton is being subjected to the action of the beaters and said belt, and means for adjusting and maintaining the belt under proper tension.

3. A cotton huller and cleaner, including an endless movable belt having picker points, beaters arranged in spaced relationship to successively receive and discharge material against the surface of said belt to separate the hulls from the cotton, a screen below said beaters, to separate the dirt and trash from the cotton as the cotton is being subjected to the action of the beaters and said belt, a conveyor cooperatively arranged with respect to said belt, and means which cooperates with said belt to remove the hulls from the belt into said conveyor, the conveyor serving to carry said hulls to a suitable point of disposal.

4. A cotton huller and cleaner, including an endless movable belt having picker points, beaters arranged adjacent said belt to separate the hulls from the cotton by throwing the same against said belt and allowing unimpaled material to be again received in said beaters for renewed discharge, each of said beaters consisting of a hollow body on which beater members are arranged, said body having openings therein through which air passes in streams induced by the motion of the beater, to blow the cotton against the belt.

5. In a cleaning machine of the class described, an endless movable belt having picking means thereon, a chamber having an inlet below said belt, rotatory means within said chamber operable to constantly beat fibrous material fed into said chamber through said inlet, and also to cause movement of the material toward the lower lead of said belt, while inducing currents of air to circulate through the material, said belt serving to carry away material picked up by said picking means during the operation of the rotatory means and movement of said belt.

6. In a cleaning machine of the class described, an endless movable belt having picking means thereon, a chamber having an inlet below said belt, rotatory means within said chamber operable to constantly beat fibrous material fed into said chamber through said inlet, and also to cause movement of the material toward the lower lead to said belt, while inducing currents of air to circulate through the material, said belt serving to carry away material picked up by said picking means during the operation of the rotatory means and movement of said belt, and a screen below said rotatory means for separating waste particles from the fibrous material.

7. In a cleaning machine of the class described, an endless movable belt having picking means thereon, a chamber having an inlet below said belt, a plurality of combination rotary beaters and air blast elements within said chamber operable to constantly beat fibrous material fed into said chamber through said inlet, and also to cause movement of the material toward the lower lead to said belt, while inducing currents of air to circulate through the material, said belt serving to carry away material picked up by said picking means during the operation of said combination rotary beaters and air blast elements and movement of said belt.

8. In a cleaning machine of the class described, an endless movable belt having picking means thereon, a chamber having an inlet below said belt, a plurality of combination rotary beaters and air blast elements, together with an undulated screen below said elements in close proximity thereto for separating waste particles from the fibrous material within said chamber operable to constantly beat fibrous material fed into said chamber through said inlet, and also to cause movement of the material toward the lower lead to said belt, while inducing currents of air to circulate through the material, said belt serving to carry away material picked up by said picking means during the operation of said combination rotary beaters and air blast elements and movement of said belt.

9. A cotton huller and cleaner including an endless movable belt having picker elements thereon, means operating below said belt for successively casting material into the operative area of said belt to be continuously impaled upon and carried off by said belt, and doffing and stripping means also operating adjacent said belt to remove material therefrom.

10. A cotton huller and cleaner including continuously moving impaling means, and a series of juxtaposed beater elements below the impaling means for receiving and successively throwing material against the impaling surface of said impaling means to be thereby

withdrawn from the operative area of said beater elements.

11. A cotton huller and cleaner including juxtaposed beater elements arranged to impart to the entering cotton a cleaning action as the latter is thrown from one to the other of said beater elements, and means operating above said beater element assembly to continuously impale and carry off cotton adhering thereto when thrown by said beater elements, and means for removing cotton adhering to said impaling means.

12. In a cleaning machine of the character described, a series of relatively arranged rotary beater elements for beating material through said machine and inducing the circulation of air through said material, means carrying picker elements moving adjacent said beater elements for impaling and carrying off material cast by said beater elements out of their operative range.

13. In a cleaning machine of the character described, a plurality of relatively disposed, cooperating beater elements constructed and arranged to create continuous air currents through material while beating the latter in a progressive rotary manner through said machine and means for continuously impaling material thrown by said beater elements and conveying the same to a point of disposal.

14. In a cleaning machine of the character described, a series of co-operating beater elements constructed and arranged to maintain a continuous air draft through material while cleaning the same by a series of progressive rotary movements toward the outlet end of said machine, impaling means continuously receiving material thrown out of the operative area of said beater elements, and means for removing strippings and cotton from said impaling means.

JOSHUA C. CONRAD.
